UNITED STATES PATENT OFFICE.

JOHN D. HILLIARD, JR., AND CHARLES E. PARSONS, OF GLENS FALLS, NEW YORK.

ELECTRIC OIL-SWITCH.

No. 882,388.

Specification of Letters Patent. Patented March 17, 1908.

Application filed January 29, 1906. Serial No. 298,532.

To all whom it may concern:

Be it known that we, JOHN D. HILLIARD, Jr., and CHARLES E. PARSONS, citizens of the United States, residing at Glens Falls, in the 5 county of Warren and State of New York, have invented certain new and useful Improvements in Electrical Oil-Switches, of which the following is a specification, reference being had therein to the accompanying 10 drawing.

Our invention relates to electrical switches, and has for its object the production of such a switch which shall offer security against short circuits or destructive arcs, when used 15 in connection with circuits carrying considerable power, and which shall at the same time be perfectly simple and economical to manufacture.

Our invention belongs in the class of oil 20 break switches, and possesses a number of features of novelty, apart from the general improvement in design. The parts are all highly insulated, and the fixed contact has no metal connection with the shell or casing.

25 The moving contact is likewise electrically disconnected from everything except the incoming end of the circuit lead of which it forms the terminal. This moving contact is provided with an insulating casing substantially surrounding the contact surfaces, and 30 preferably funnel-shaped, with its broad end pointed away from the fixed contact, and its narrow end projecting toward the same.

With this construction, when the movable 35 contact leaves the fixed contact, describing an arc through the oil in which it is immersed, a portion of the oil is by virtue of the motion projected through the funnel into the path of the arc, which is confined by the projecting 40 walls of the insulating casing and prevented thereby from swinging to one side out of the oil blast.

In order to quickly make and break, particularly the latter, and at the same time to 45 maintain the switch locked in its closed or open positions, we provide on the outside of our casing an arrangement of lugs, locking bolt and cam, together with a spring connection between the operating lever and the 50 side switch parts, such that the parts are locked in either position until the lever is swung through a considerable distance in a direction to reverse the parts, thus putting the operating spring under tension. When

such tension has been attained, suitable cams 55 on the lever act to positively unlock the parts and permit them to swing over, either opening or closing the switch, as the case may be, and then again locking until the motion of the lever be reversed. Subsidiary points of 60 design in which we have embodied improvements of a supplemental nature, will be apparent to those skilled in the art after reading detailed description hereinafter. Among these we may mention the construction of 65 the supporting parts for the movable contact or electrode. These comprise a yoke, with studs or trunnions projecting on each side, forming in effect a crank or crank-shaft of what we may term engine type. The ends 70 of the studs or trunnions are journaled in the opposite walls of the casing, at its upper portion, and since the motion is rotary within the bearings, it is thus possible to effect a somewhat tight-fitting joint without any 75 special packing, and without creating large friction in the working parts. The shape we have given to our yoke enables one of the wire leads to be brought in through a bushed opening in the casing and down through a 80 hole in the yoke, the shape of which permits free movement of the wire therein, a point of some importance in the easy working of the switch, and in the making of satisfactory connections direct from the wire leads to the 85 switch terminals without the interposition of any other conducting link.

The working parts of the switch are all carried within or upon the body of the casing, which itself is carried upon any suitable support. 90 The casing is partly filled with oil, in which the contacts are immersed, as stated, and is provided with a removable plug closing an aperture in the bottom, through which the oil may be removed, if desired. The top 95 of the casing is closed by a cap or lid having a wide over-hang with edges forming a pent-roof over the side openings through which the wire leads pass, and protecting the same.

Our invention is illustrated in the accompanying drawings, in which—

Figure 1 is a side elevation with the cover partially broken away so as to reveal the switch operating lever; Fig. 2 is a side elevation with the lever removed and the front of 105 the casing broken away; Fig. 3 is a central transverse section through the casing and the switch operating lever; Fig. 4 represents

detailed views of the separated parts of the switch operating lever and its associated mechanism; Figs. 5 and 6 are details of the switch contacts, and Figs. 7 and 8 are modifications of these contacts.

Referring to the drawings, 1 represents a casing of suitable material, preferably of metal, which is provided with projecting end flanges 2, provided with apertures 3 through 10 which the bolts or screws may be passed to secure the device upon a support. The top 4 is provided with overhanging flanges 5 depending a sufficient distance to cover the conductor apertures 6 in the casing. This 15 top is secured by means of bolts 7 tapped into the lugs 8 formed on the casing. A suitable insulation 9 lines the casing throughout so as to prevent arcing from the contacts. The apertures 6 and 11 are further insulated 20 by bushings 60, through which the conductors are passed.

10 represents a supporting plate provided with an aperture 11 registering with one of the holes 6 in the casing and secured thereto 25 by screws 12. Adjacent the bottom of this supporting plate 10 is fastened an insulator 13, in the end of which is held, (preferably by a lead or solder filling), the stationary contact 14 of the switch, which in this instance 30 comprises a base block and a pair of split spring tongues 15, of metal. These springs 15 are slightly convergent toward their outer or free end so that they may enter the funnel-shaped moving contact 16, provided with a 35 sheath 51 of solid insulating material.

The springs 15 are supported on the block 14, and may be replaced when desired. In order to effect good electrical connection therewith, we provide a terminal member 18, 40 into a socket 19 of which the bared end of a conductor 21 is soldered, this member then being secured to the base block 14 of the contact by means of bolts 17.

Centrally located with relation to the 45 length of the casing is a yoke 22 having stub shafts or trunnions 23-24 journaled in the casing. This yoke member is a casting having downwardly-projecting cheek-plates, transversely channeled crank lugs, and a 50 hole between them communicating with the space between the cheek-plates so as to form an enlarged opening, preferably elliptical in cross-section, down through the body of the moving parts. Secured between the cheek- 55 plates, preferably by rivets, is a wooden or other insulator 25, having a central channel communicating with the opening to the yoke, and carrying at its lower end a funnel-shaped contact 16, provided with a terminal socket member 26, in which the end of the wire 27 can be secured by solder, as usual.

Keyed to the stub shaft 24 is a casting 29 provided with a depending portion 30 in which is mounted a sliding bolt 31 normally 60 pressed outward by a spiral spring 32 and

limited by a stud 33 secured to the bolt and working within a longitudinal slot 34 formed in the depending member 30. This casting 29 is provided with a depression 35 in its face, and a hole 36 adapted to receive one 70 end of a spiral spring 37. Part of the spiral spring lies within the depression in the casting 29 and the other half lies within a similar depression 38 formed within the operating lever 39 and having the opposite end of the spiral spring 37 set within a hole 40 drilled in the head of the lever. This lever is provided with a cam 41 which is adapted to engage the stud 33 so as to throw the sliding bolt 31 out of engagement with the lugs 42 80 and 43. Adjacent to the locking lugs 42 and 43 in either side thereof are limiting lugs 44 adapted to limit the throw of the switch.

In the modifications shown in Fig. 7 we have shown the limbs 45 of the stationary 85 contact quite close together with their ends 46 flaring so as to allow an easy passage of the knife blade of the swinging contact 47 of the switch in Fig. 8, which in this instance is formed by bending two pieces of sheet 90 metal 48 around the end of the insulating member 25 and bringing them together at the center so as to form substantially one piece of metal which takes in between the limbs 45 of the stationary contact. These 95 metal members 48 are flared at their bottom at right angles and constitute two flanges of substantially the same width as the insulating member 25. Around these members is secured a funnel-shaped wrapping 49, of 100 suitable insulating material, such as treated fiber sheets or the like, so that it projects beyond the contact 47. The stationary contact is also provided as in Fig. 5 with a terminal member 18 to which the line conductor is secured as mentioned above, and one of the strips of metal 48 is bent around the insulating member 25 to form a terminal post 26.

The operation of our invention is as follows: Assuming the parts to be in the position shown in Figs. 1 and 2, and that it is desired to close the contacts together, the handle 39 is thrown to the left. The first effect of this is to put the spring 37 under tension, 110 but as the spring is expanding, and therefore its coils are opening, the amount of tension is not so great as when it is working in the reverse direction. This, however, is of no importance in closing the switch. When 115 the handle 39 is moved a sufficient distance for the cam 41 to have pushed the stud 33 high enough to lift the bolt 31 out of engagement with the lug 42, the arm 30 and the connected parts 22, 25 and 16 within the 120 casing move over, until the contact 16 reaches the spring contacts 15, and the connection is complete. The bolt 31 then engages behind the lug 43, and the switch is locked in the 125 closed position. In order to open it, the 130

handle 39 is thrown to the right, whereupon the action we have mentioned is reversed, *i. e.*, the spring 37 is placed under considerable tension, which reaches a maximum just 5 as the cam 41 leaves the stud 33 and disengages the bolt 31 from the lug 43. The result is that the energy stored up in the spring is released instantaneously, and the insulating arm 25 carrying the movable contact 16 10 is snapped quickly to the right, in Figs. 1 and 2, separating the contacts very sharply. If considerable energy is being communicated through the switch there will, of course, be a heavy arc formed, but as the movable 15 contact progresses through the oil, a quantity of the latter is forced through the funnel into the path of the arc, which at the same time is confined by the projection of the inclosing insulator toward the fixed contact, 20 and prevented from springing one way or the other to avoid the oil blast. The result is that the arc is extinguished almost as soon as it is formed.

We are aware that many changes may be 25 made in matters of detail in this switch, and we wish to include the same in our statement of invention and in the scope of the claims herein.

Having thus described our invention, what 30 we claim and desire to secure by Letters Patent is:

1. An electrical switch comprising a stationary contact, a hollow externally insulated movable contact coöperating there- 35 with, insulating fluid surrounding the contacts, and means for quickly separating the same and producing accelerated motion of the movable contact through said fluid, whereby a jet is produced in the path of the 40 arc to extinguish it.

2. An oil switch comprising a fixed contact and a coöperating movable contact, oil surrounding the contacts, and insulating means carried by the movable contact adapt- 45 ed to confine the arc, and to direct a jet of oil into the path of the same so as to extinguish it.

3. In an electrical switch, a fixed contact and a movable contact, oil surrounding the 50 contacts, means to produce rapid motion of the movable contact in the oil in breaking, and an insulating funnel or duct carried on the movable contact, whereby the path of the arc is restricted, and a jet of oil is pro- 55 duced therein to extinguish it.

4. An electrical switch comprising a fixed contact, a movable contact, oil surrounding said contacts, insulating means carried by the movable contact for restricting the path 60 of the arc formed in breaking, and for producing a jet of oil due to the motion of the contact, in said restricted path, to extinguish the arc.

5. An electrical switch comprising a fixed 65 contact and a movable contact, both having

extended contact surfaces lying in the plane of motion, oil surrounding said contacts, and insulating means carried by and surrounding the movable contact so as to restrict the path of the arc formed upon breaking and at 70 the same time direct a jet of oil due to the motion of the contact, across the surface thereof and into the path of the arc to extinguish it.

6. An electrical switch comprising a fixed contact, a movable contact, oil surrounding the contacts, hollow insulating means carried on the movable contact, and a motor mechanism adapted to produce rapidly accelerated motion thereof through the oil, 75 whereby the arc formed upon breaking is confined to the space between the contacts, and a jet of oil is directed into the said space to extinguish the arc.

7. An electrical switch comprising an inclosing casing, oil in said casing, a fixed contact secured within the casing beneath the surface of the oil, a movable contact carried upon a rocking arm so as to swing to and from the fixed contact beneath the oil, a 80 transverse shaft for said arm, hollow insulating means mounted upon the movable contact and serving to confine the arc formed upon breaking and also as a duct for the passage of oil into the path thereof, and a motor 85 mechanism adapted to act through said shaft to swing the movable contact quickly 90 away from the fixed contact to break.

8. An electrical switch comprising a metal casing, an insulating lining in said casing, a 100 fixed contact mounted upon an insulator within the casing, a circuit connection therefor, a movable contact mounted upon a second insulator forming a swinging arm carried by a transverse shaft, an insulating funnel or guard carried upon and surrounding the movable contact, a circuit connection extending to said movable contact and mechanically supported by but electrically insulated from said shaft, oil in the casing covering the contacts, and a motor mechanism for said shaft comprising an actuating lever, a spring connection from said lever to the shaft, locking means for the shaft, and a cam carried by the lever adapted to trip said locking means after the spring has been placed under tension by the full movement of the lever, so as to produce rapid motion of the movable contact through the oil in breaking. 110

9. An electrical switch comprising a metal casing, an insulating lining in said casing, a fixed contact mounted upon an insulator within the casing, a circuit connection therefor, a movable contact mounted upon a second insulator forming a swinging arm carried by a transverse shaft, an insulating funnel or guard carried upon and surrounding the movable contact, a circuit connection extending to said movable contact, and mechanically supported by but electrically in- 120

sulated from said shaft, oil in the casing covering the contacts, and a motor mechanism for said shaft comprising an actuating lever, a spring connection from said lever to the 5 shaft, locking means for the shaft, and a cam carried by the lever adapted to trip said locking means after the spring has been placed under tension by the full movement of the lever, said locking means acting to

lock the switch either opened or closed, until 10 the lever is turned in the reverse direction.

In testimony whereof we affix our signatures in presence of two witnesses.

JOHN D. HILLIARD, JR.
CHARLES E. PARSONS.
